UNITED STATES PATENT OFFICE

173,269

TIRE

Leonard John Lambourn, Erdington, Birmingham, England, assignor to Dunlop Tire and Rubber Corporation, Buffalo, N. Y., a corporation of New York

Application December 8, 1953, Serial No. 27,987

Claim priority, application Great Britain
October 7, 1953

Term of patent 14 years

(Cl. D90—20)

To all whom it may concern:

Be it known that I, Leonard John Lambourn, a subject of the Queen of Great Britain, have invented a new, original, and ornamental Design for a Tire, of which the following is a specification, reference being had to the accompanying drawing, forming a part thereof.

Fig. 1 is a perspective view of a tire showing my new design;

Fig. 2 is a fragmentary perspective view thereof, and

Fig. 3 is a fragmentary top plan view thereof.

I claim:

The ornamental design for a tire, as shown.
